UNITED STATES PATENT OFFICE.

SUSAN A. HENNING, OF CHICAGO, ILLINOIS.

BEDCLOTHES-HOLDER.

SPECIFICATION forming part of Letters Patent No. 365,814, dated July 5, 1887.

Application filed November 23, 1886. Serial No. 219,712. (No model.)

To all whom it may concern:

Be it known that I, SUSAN A. HENNING, a citizen of the United States, and a resident of Chicago, in the county of Cook and State of Illinois, have invented certain new and useful Improvements in Bedclothes-Holders, which are fully set forth in the following specification.

My invention relates to appliances for securing bedclothes and mattresses at the foot 10 of the bed; and its object is to provide fastenings which can be easily manipulated and will be concealed from view while in use. This object I attain by the means illustrated in the accompanying drawings, wherein—

15 Figure 1 is a longitudinal sectional view of part of a bedstead provided with my improvement, taken just inside one of the side boards of the bed. Fig. 2 is a section through a detached fastener. Fig. 3 is a plan view of such 20 a fastener.

Like parts are indicated by the same letter in all the figures.

A is the frame-work of the bed.

B is the foot-board.

25 C is the side board.

D is the mattress, and E the covers.

H is the body of the fastener, provided with screw-holes H' H', whereby it may be secured in suitable position. From the lower end of 30 the body H rise the arms F F, at the outer ends of which is pivoted the clamp G by means of the pin K.

L is a ledge on the upper part of the body H, adapted to receive the end of the clamp G.

35 M is a spiral spring secured at the points M' M' to the clamp G and body H.

O is a flat spring, the ends of which rest, respectively, in the slots O' and O''. These springs coact to keep the clamp G in the position shown in Fig. 2, or to cause it to grip the clothes, as shown in Fig. 1. Either of these 40 springs may be dispensed with. The ledge L may be quite different in shape, and in some instances it will be found preferable to have it above rather than below the extremity of the clamp G. The clamp or fastener, as shown in Fig. 1, is somewhat enlarged to permit its several parts to be clearly illustrated.

The use and operation of my invention are 45 as follows: The clothes-fasteners, as shown, are

attached to the foot of the bed—one on each side. They may of course be attached in any other convenient position. The end of the clamp G may, if desired, extend below the side rail. The covers are first spread in proper order on the mattress, and then, by first swinging back the clamp G, which can be done by applying pressure to its lower end and then drawing the covers between the clamp and ledge and releasing the clamp, the covers will 55 be securely grasped and held at the foot.

The clamp and body could be attached to each other by means other than those shown; but the essential point in this part of my invention is securing the two parts of the clamp- 65 ing device together by means of a spring-hinge.

O' is a hook on the end of the clamp G, and O'' is a strap leading therefrom attached to the mattress D. This strap is designed to keep the mattress from sliding toward the head, and 70 it is especially designed for use in folding beds to keep the mattress from sliding down. When in use on a folding bed, it will be seen that the strap secures the mattress, and also that the weight applied thereon tends to increase the grip of the clamp on the bedclothes, and thus the better to secure them. 75

X is a rope attached to the lever clamp G, and passing through the aperture Y, and terminating in the ring S. It can be drawn down 80 to open the clamp and secured on the pin Z, thus holding the clamp open until the bed is made, when it is released.

I claim—

In a bedclothes-holder, the combination of 85 a frame secured to the bed-frame, a lever pivoted on such frame, a spring which forces one end of the lever against the holder-frame, and a hook on the opposite end of the lever, to which the mattress is secured, substantially as described. 90

In testimony whereof I have hereunto set my hand, in the presence of two witnesses, at Chicago, Illinois, this 12th day of November, A. D. 1886.

SUSAN A. HENNING.

Witnesses:

FRANCES W. PARKER,
G. G. JACKSON.
